UNITED STATES PATENT OFFICE.

DANIEL CRANE, OF SAGINAW, MICHIGAN, ASSIGNOR OF ONE-HALF TO JAMES GIBSON
CRANE, OF KENDAIA, NEW YORK.

DESIGN FOR A TABLE.

Application filed March 29, 1926. Serial No. 17,108. Term of patent 7 years.

To all whom it may concern:

Be it known that I, DANIEL CRANE, a citizen of the United States, residing at Saginaw, in the county of Saginaw, State of Michigan, have invented a new, original, and ornamental Design for Table, of which the following is a specification, reference being had to the accompanying drawing, forming part thereof.

The figure is a perspective of a table, showing my new design.

I claim:

The ornamental design for a table as shown.

DANIEL CRANE.
